UNITED STATES PATENT OFFICE.

ZARDIA CRAIN, OF MURPHYSBORO, ILLINOIS, ASSIGNOR OF ONE-FOURTH TO DANIEL BOWER AND ONE-FOURTH TO A. J. WOODARD, OF MURPHYSBORO, ILLINOIS.

BOOK-HOLDER FOR ADDING-MACHINES.

No. 846,012.

Specification of Letters Patent.

Patented March 5, 1907.

Application filed June 23, 1906. Serial No. 323,092.

To all whom it may concern:

Be it known that I, ZARDIA CRAIN, a citizen of the United States, residing at Murphysboro, in the county of Jackson, State of Illinois, have invented certain new and useful Improvements in Book-Holders for Adding-Machines, of which the following is a specification, reference being had therein to the accompanying drawing.

10 This invention relates to a book-holder for computing-machines, and particularly to an attachment adapted for use with machines of this character.

15 The invention has for an object to provide a book-holding carriage mounted for travel in both vertical and horizontal planes relative to the computing-machine to which it is attached, together with means for automatically controlling the movement of said carriage 20 in the operation of the computing-machine.

25 Another object of the invention is to provide an improved construction and arrangement of book-holder provided with platens adapted to be inserted beneath the leaves of 30 the book for retaining the book in proper position within the carriage.

Other and further objects and advantages of the invention will be hereinafter set forth, and the novel features thereof defined by the 35 appended claims.

In the drawings, Figure 1 is a perspective of the invention with the book-holder removed from the carriage. Fig. 2 is a rear elevation thereof with the book-holder in position. Fig. 3 is a vertical section on the line 3 3, Fig. 2. Fig. 4 is a similar view showing the book-holder removed from the carriage for proper adjustment of the book therein. Fig. 5 is a detail section showing the mounting of the back board upon which the book rests. Fig. 6 is a similar view, on an enlarged scale, of the locking-latch for the holder when in horizontal position. Fig. 7 is a detail perspective of the case of the book-holder. Fig. 8 is a similar view of the platens. Fig. 9 is a detail perspective of the holder-frame. Fig. 10 is a cross-section on the line 10 10, Fig. 8. Fig. 11 is a detail elevation of the column-stop mechanism for the carriage. Fig. 12 is a detail perspective of the dogs carried by this mechanism. Fig. 13 is a similar view of the rear face of the column-stop and its supporting-rack. Fig. 14 is a similar view

of the operating-lever for the stop mechanism. Fig. 15 is an enlarged cross-section on the line 15 15, Fig. 11. Fig. 16 is a detail rear elevation of the escapement mechanism controlling the vertical movement of the carriage. Fig. 17 is a front elevation of the same. Fig. 18 is a section of the parts shown in Fig. 17 with the controlling-gear in mesh. Fig. 19 is a similar view with this gear thrown out of mesh to receive the frame; and Fig. 20 is a detail elevation of the rear of the carriage, showing the platens supported thereon.

Like numerals of reference indicate like parts throughout the several views of the drawings.

The numeral 1 designates a computing-machine, which may be of any desired character—for instance, the type known as the “Burroughs” machine, which is provided with the operating-lever 2 at one side, by which the printing operation is controlled after the keys 3 have been properly operated to set the numerals. In the present application of this invention this machine is shown as supported upon a board or base 4, carried by a fixed frame 5, having at its opposite ends standards 6 and 7, the latter being provided with a rack 8, as hereinafter described. The machine may be connected to this standard in any desired manner—for instance, by braces 9 at opposite sides thereof—and upon the standards the vertical bars 10 of the carriage-frame 11 are slidably mounted with the usual ball-bearings, if desired. The top and bottom rails of this frame are connected by the vertical bars 12, within which frame the carriage 13 is adapted to travel, the top and bottom rails 14 thereof being grooved to receive the ball-bearings 15, as shown in Figs. 3 and 4. The rail 11 of the frame is adjustably mounted on the vertical bars 12 by means of set-screws 16 and 17, the latter extending through an elongated slot in the face of the rail 11, so as to permit a proper adjustment of the ball-bearing tracks, as shown in Fig. 4. For the purpose of placing the carriage under proper tension a spring-drum 18 is secured by a bracket 19 to the under face of the frame 11 and connected by a flexible strip 19' with a depending hook 20 from the carriage, so that the same is held under tension in the usual manner.

For the purpose of controlling the travel of

the carriage within its frame a column-stop mechanism is provided and is adapted to be automatically controlled from the computing-machine by means of the crank-arm 21, carried upon an oscillating shaft 22, extended from the mechanism within the machine, and connected by a link 23 with the angle-arm 24, disposed upon a pivoted bar 25, which extends for the length of the standard and has its bearings 26 at the opposite ends thereof. This bar is shown in detail in Fig. 11 and in the operation of the computing-machine is adapted to swing toward and from the standard upon which it is mounted. The free edge of this bar is disposed in the path of the rock-lever 27, which is pivotally mounted upon the bearing portion 28 intermediate of its ends by means of a bearing 29, applied to the vertical bar of the carriage-frame 10, and the upper end 30 of this lever connects with the column-stop mechanism, as hereinafter described. The lower end of this bar is provided with a casing, as shown in Figs. 14 and 15, at 31, within which the pawl 32 is pivotally mounted at 33 and provided with an inclined face 34 and a stop-lug 35 to limit its outward movement. The pawl is normally held in its outward position, as shown in Fig. 15, by means of a spring 36, carried by the casing and bearing against the under face of the pawl. Beyond this casing a plate 37 is formed and provided with an elongated slot 38, through which the stop-pin 39 extends, said pin being mounted in the frame and provided with a head 40 to limit the outward swing of the rock-lever. It will thus be seen that in the oscillation of the bar 25 the rock-lever is swung on its pivot until the bar passes the pawl, and this movement of the rock-lever is communicated to the stop mechanism.

The column-stop mechanism hereinbefore referred to comprises the horizontally-disposed rod 41, adapted to oscillate in bearings 42 and also to have a limited reciprocatory movement therein. This rod is provided with a parallel connecting-pin 43, pivotally connected with the free end of the rock-lever 30, as shown at 44 in Figs. 1 and 11. The rod 41 is provided with a cushioning-spring 45, bearing at one end against a bearing 42 and adapted to be adjusted in tension by the lock-nuts 46, threaded upon the rod. The rod also carries a dog-casing 47, within which the dog 48 is pivotally mounted at 49 and normally thrown outward from said casing by means of a tension-spring 50 bearing thereon. This dog 48 is disposed at the lower portion of the casing, while at one side of the casing a secondary dog 51 is provided, which in a swinging movement of the rod is adapted to be thrown into the plane previously occupied by dog 48, so as to engage one of the column-stops 52, any desired number of these stops being

used, depending upon the number of columns to be printed. These stops are retained in position upon a slideway 53, extending longitudinally of the top rail 14 of the carriage, and which way is provided with a flange 54, having an interiorly roughened or toothed face 55, adapted to coöperate with a similar face 56, carried by the flange 57 of the stop. These teeth or engaging faces are preferably disposed diagonally to a vertical line, as shown in Fig. 13, so as to retain the stops 52 at any position they may be disposed thereon. The casing 47 is normally thrown outward from the carriage-frame 11, upon which it is mounted, by means of a spring 58 at the rear thereof, which spring in its action also restores the rock-lever 27 to its initial position. From the above mechanism it will be seen that an oscillation of the dog-casing 47 in one direction will carry the dog 48 out of engagement with the first stop 52 and permit a movement of the carriage until the second stop engages the secondary dog 51, by which the carriage is held until the casing is restored to its normal position, when this second stop will move into engagement with the dog 48 in position for a subsequent operation.

For the purpose of controlling the vertical movement of the carriage line by line the frame 11, carrying the same, is slidingly mounted upon the standards, as before described, the standard 7 being provided with the rack 8, as shown in detail in Figs. 16, 17, 18, and 19, with which a pinion 60 is adapted to mesh, said pinion being also in mesh with the gear 61, mounted upon the fixed part or standard 10 by means of a bearing-bracket 62. The shaft of this gear is provided with an escapement-wheel 63, adapted to coöperate with the dog mechanism 64 of ordinary construction, the shaft 65 of which carries at its rear a trip-lever 66, having oppositely-inclined faces 67 and 68 and normally held at one extreme of its travel by means of a tension-spring 69, extending therefrom to the frame 11. This trip-lever is adapted to be engaged by one or more stops 70, pivotally mounted upon the top rail 14 of the carriage at 71 and extending into the path of the trip-lever, while the lower end thereof abuts against the stop-lug 72. A plurality of these stops are provided in order that the proper spacing between lines may be determined. For instance, as here shown, two stops may be used to effect a full space, while if a half-spacing is desired in order to interline one of the stops may be thrown out of operative position, and thus held by means of a pivoted arm 73, adapted to lie beneath the stop, as shown at the right of Fig. 16, and in contact with the stop-lug 72, while if the stop is to be used this arm is thrown away from the lug 72 and in contact with the pin 74, by which it is held. It

will thus be seen that each movement of the trip-lever will oscillate the dog 64 to produce a downward feed of the carriage for one tooth of the escapement-wheel. When it is desired to operate these dogs by hand, the same can be readily effected by means of the hand-lever 75, applied to the shaft 65 at the front of the machine. When the carriage and parts supported thereby are to be restored to their initial position, the pinion 60 may be disengaged from its rack 8 by means of the lever 76, upon which the same is mounted at the lower end, said lever having its pivot upon the shaft of the gear 61 and being held normally under tension by means of the spring 77, and it will be seen that a compression of this spring will throw the pinion 60 away from the rack. In order to maintain a proper relation of these parts, a bearing-wheel 78 is carried by the bracket 79 upon the carriage-frame to engage the rear face of the standard. It will be observed that the vertical feed of the book is from the top to the bottom, so that the force of gravity is utilized in the movement, and the line-by-line feed extends upward of the page, the book being adjusted so that the bottom line thereon will be the first printed, the raising of the book being accomplished by hand.

Within the carriage 14 the book-holder frame 80 is pivotally mounted by means of the lugs 81 at one end thereof provided with pintles 82, adapted to seat in the pivoting brackets 83, carried by the lower rail of the carriage, said brackets being provided with an elongated bearing-recess 84, as shown in Fig. 3, whereby a pintle may be removed from the bearings by a longitudinal movement therein. This frame is adapted to receive the book and is provided at its pivot end with a cross rod or bar 85, mounted in the side walls of the frame and in the bracket 86, carried thereby, upon which the platens 87 are pivoted at each side of the bar 88, carried by the frame. These platens are provided with pivoting-bearings 89, as shown in Fig. 8, and are mounted upon the carriage, as shown in Fig. 4, so as to lie beneath the sheet of the book which is to receive the impression from the computing-machine. The platens are each tapered in cross-section toward the central bar 88, as shown in Fig. 10, so as to place their smallest diameter next the bound edge of the sheet. In other words, they taper inwardly toward the center of the frame. Upon the extended ends 90 of the rods 85 the casing 91 is mounted by means of the elongated slots 92 in the side walls thereof, said casing being provided with the central bar 93 in alignment with the bar 88 and extending from a cross-bar 94. The casing fits snugly over the frame 90 and is provided with a lug 95 to limit its movement relative to the carriage, as shown in

Figs. 3 and 4. This casing holds the sheet to receive the printing firmly against the platens.

The book-holder and parts carried thereby are adapted to be raised into the printing position (shown in Fig. 3) in the carriage by means of the tension-arm 96, pivotally mounted at 97 upon the lug 98, carried by the bar 14 of the carriage, said arm being provided with a stop-lug 99, adapted to engage a cross-bar 100, carried by the frame below the track or way thereof. The upper end of this arm is pivotally connected at 101 to a sleeve 102, slidably mounted upon the rod 103, carried by bearings 104 upon the bar 88 of the frame 80. The coil-spring 105 extends from one of these bearings to the sleeve 102, so that when the book-holder is lowered into the position shown in Fig. 4 the spring is placed under tension. When in this position, the holder is adapted to be locked and held against the automatic raising by the spring by means of the pivoted catch 106, mounted on the side of the bar 88 and adapted to engage the tooth 107, carried by the sleeve 102, and normally held in contact with said tooth by the spring 108 bearing upon the latch. The crank-arm 109 from this latch is connected by rod 110 with the operating-lever 111, pivotally mounted at 112 upon the bar and adapted to coöperate with the fixed handle 113, carried by the holder-frame. When it is desired to raise the carriage into the position shown in Fig. 3, it is only necessary to release the latch 106, and the spring will throw the book-holder upward into engagement with the carriage, the position of the tension-arm being such as to prevent a return movement except when drawn backward by an exterior force.

The book, as shown at 114 in Figs. 3 and 4, is supported upon back boards 115, Figs. 2 and 3; these boards being provided at opposite ends with the crossed levers 116, Fig. 5, pivotally mounted at 117 upon the board and at 118 upon the frame 80, while the opposite ends of these levers have a sliding and pivotal bearing at 119 on the board and 120 on the frame. These levers provide for the movement of the boards toward and from the casing of the book-holder in parallelism, the levers being pivoted together at their point of crossing 121. The boards are normally pressed inward toward the casing by means of the spring-levers 122, as shown in Fig. 2, having a bearing 123 at the center of the boards and adjustably secured to the tension-heads 124, which are mounted upon the rods 125, carried by the brackets 126 of the frame 80, said heads being retained under tension by means of the coil-spring 127, connected thereto at one end, bearing against the frame at its opposite end. If it is desired to use the attachment without the book-holder, the same can be readily removed from the

carriage and an ordinary platen 129 of any desired construction mounted upon the brackets 130, carried by the rear of the carriage-frames 13, as shown in Figs. 1 and 20.

- 5 In the operation of the machine when it is desired to apply a book thereto the holder is swung downward, as shown in Fig. 4, and the casing and platens thereof swung upward to permit the placing of the book upon the 10 back boards. The platens are then swung into contact with the book with the pages to be printed upon the top of the platens and the casing closed, so as to hold the book in smooth firm contact, owing to the tension of 15 the back boards against the frame and casing. The latch is then released, permitting the bracket of the tension-arm to automatically throw the book-holder into vertical position within the carriage. The carriage-frame is then raised, so as to bring the bottom 20 line of the book in printing position, and the carriage moved to the extreme right of its travel. The keys of the computing-machine are then operated to set up the proper 25 numerals to be printed, and upon the operation of the lever of such machine the printing mechanism thereof is thrown into contact with the book in the usual manner. In the return movement of this lever the pivoted 30 bar carried by the standards is oscillated, which in turn operates the column-stop dogs, permitting the carriage to move to the left into the next position for printing. This continues for the desired number of 35 columns to be printed and effects an automatic feed of the carriage by the usual operation of the computing-machine. In the return movement of the carriage from left to right the stops carried thereby actuate the 40 trip-lever, which operates the escapement mechanism controlling the rack and pinion to permit the proper downward movement of the carriage-frame and book carried thereby into the next lowest position for printing. 45 It will thus be seen that the book while supported in a vertical position is adapted to receive the impression from the computing-machine and also the totals or results ordinarily obtained in the operation of such a machine. The construction and arrangement 50 of parts is particularly adapted to render the feed of the carriage in both a horizontal and vertical plane automatically relative to the machine to which it is attached, while the 55 book-holding means effectually presents the sheet thereof to be printed in proper position to receive the impressions from such a machine.

Having now described my invention and 60 set forth its merits, what I claim, and desire to secure by Letters Patent, is—

1. In a device of the class described, a vertically-disposed carriage, means for effecting a travel thereof in a horizontal plane, and 65 means automatically operated in the hori-

zontal travel of the carriage for controlling the travel thereof in a vertical plane.

2. In a device of the class described, a vertically-disposed carriage, means for effecting a travel thereof in a horizontal plane, a plurality of devices upon the carriage for controlling a travel thereof in a vertical plane during its horizontal travel, and a book-holder mounted in said carriage. 70

3. In a device of the class described, fixed standards, a carriage-frame mounted to travel vertically thereon, a carriage mounted to travel horizontally on said frame, means upon the frame to control said horizontal travel, and connections from an auxiliary machine disposed upon the standards in the path of travel of the controlling means upon 75 said frame. 80

4. In a device of the class described, fixed standards, a carriage-frame mounted to travel vertically thereon, a carriage mounted to travel horizontally on said frame, means upon the frame to control said horizontal travel, connections from an auxiliary machine disposed upon the standards in the path of travel of the controlling means upon 85 said frame, means upon one standard to control the vertical travel of the frame thereon, and means upon the carriage for automatically operating said vertical controlling means 90 in the horizontal travel of the carriage. 95

5. In a device of the class described, a vertically-disposed carriage, means for effecting a travel thereof in a horizontal plane, means for effecting a travel of said carriage in a vertical plane, and a book-holder frame pivotally mounted at the lower portion of said carriage to open in a horizontal plane, and means upon the carriage to retain the holder-frame in vertical position. 100 105

6. In a device of the class described, a vertically-disposed carriage, means for effecting a travel thereof in a horizontal plane, means for effecting a travel thereof in a vertical plane, a book-holder frame pivotally mounted at the lower portion of said carriage to open into a horizontal plane, and a tension-arm upon the carriage provided with a spring for automatically retaining said holder in vertical position. 110 115

7. In a device of the class described, a vertically-disposed carriage, a book-holder pivotally mounted in said carriage, a tension-arm provided with a spring for automatically retaining said holder in a vertical position, and a locking-latch carried by said holder to engage said arm and retain the holder in a horizontal position. 120 125

8. In a device of the class described, a vertically-disposed carriage, a book-holder pivotally mounted in said carriage, a tension-arm provided with a spring for automatically retaining said holder in a vertical position, a locking-latch carried by said holder to engage said arm and retain the holder in a horizontal position. 130

zontal position, back boards mounted in said holder, and spring-actuated levers carried by the holder to retain said boards under tension.

5 9. In a device of the class described, a vertically-disposed carriage mounted for travel in both vertical and horizontal planes, means for controlling said travel in a horizontal plane, an escapement mechanism for controlling said travel in a vertical plane, means upon the carriage for automatically actuating said escapement mechanism, a printing mechanism, and means actuated therefrom for controlling the horizontal travel of said carriage.

15 10. In a device of the class described, a vertically-disposed carriage, means for effecting a travel thereof in a horizontal plane, means for controlling a travel thereof in a vertical plane, and means upon the carriage to automatically actuate the vertical feed thereof.

11. In a device of the class described, fixed standards, a carriage-frame mounted to travel vertically thereon, and a carriage mounted to travel horizontally in said frame.

12. In a device of the class described, fixed standards, a carriage-frame mounted to travel vertically thereon, a carriage mounted to travel horizontally in said frame, a rack upon one of said standards, a pinion upon said frame engaging the same, an escapement mechanism controlling said pinion, and means disposed upon said carriage to operate said escapement.

13. In a device of the class described, standards, a carriage-frame mounted to travel vertically thereon, a carriage mounted to travel horizontally in said frame, a rack upon one of said standards, a pinion engaging the same, an escapement mechanism controlling said pinion, a trip-lever carried by said escapement, and a stop upon the carriage to engage said lever.

14. In a device of the class described, standards, a carriage-frame mounted to travel vertically thereon, a carriage mounted to travel horizontally in said frame, a rack upon one of said standards, a pinion engaging the same, an escapement mechanism controlling said pinion, a trip-lever carried by said escapement, and a pivotally-mounted stop upon said carriage adapted to be thrown into or out of the path of said trip-lever.

15. In a device of the class described, standards, a carriage-frame mounted to travel vertically thereon, a carriage mounted to travel horizontally in said frame, a rack upon one of said standards, a pinion engaging the same, an escapement mechanism controlling said pinion, a trip-lever carried by said escapement, a pivotally-mounted stop upon said carriage adapted to be thrown into or out of the path of said trip-lever, and means

to engage and retain said stop out of operative position.

16. In a device of the class described, standards, a carriage-frame mounted to travel vertically thereon, a carriage mounted to travel horizontally in said frame, a rack upon one of said standards, a pinion engaging the same, an escapement mechanism controlling said pinion, a trip-lever carried by said escapement, a pivotally-mounted stop upon said carriage adapted to be thrown into or out of the path of said trip-lever, means to engage and retain said stop out of operative position, a column-stop upon said carriage, and a coöperating dog mechanism carried by the frame to engage said stop.

17. In a device of the class described, a carriage-frame, a carriage mounted to travel therein, a plurality of column-stops adjustably supported upon said carriage, a dog mechanism mounted upon said frame and provided with a yieldingly-mounted dog and rigid dog in parallel planes to coöperate with said stops, and means to oscillate said mechanism.

18. In a device of the class described, a standard, a vertically-disposed carriage-frame thereon, a carriage mounted to travel in said frame, a plurality of column-stops adjustably supported upon said carriage, a dog mechanism mounted upon the frame and provided with a plurality of dogs in different planes to coöperate with said stops, a rock-lever mounted upon the frame to oscillate said dog mechanism, and means upon said standard to engage the lower end of said lever at any point in the frame travel.

19. In a device of the class described, a vertically-disposed carriage-frame, a carriage mounted to travel therein, a plurality of column-stops adjustably supported upon said carriage, a dog mechanism mounted upon the frame and provided with a plurality of dogs in different planes to coöperate with said stops, a rock-lever mounted upon the frame to oscillate said dog mechanism, a pivotally-mounted bar carried by a fixed member, and a pawl carried by the lower end of said lever to engage said bar.

20. In a device of the class described, a vertically-disposed carriage-frame, a carriage mounted to travel therein, a plurality of column-stops adjustably supported upon said carriage, a dog mechanism mounted upon the frame and provided with a plurality of dogs in different planes to coöperate with said stops, a rock-lever mounted upon the frame to oscillate said dog mechanism, a pivotally-mounted bar carried by a fixed member, a pawl carried by the lower end of said lever to engage said bar, and means to limit the travel of the lower end of said lever.

21. In a device of the class described, a vertically-disposed carriage-frame, a carriage

- mounted to travel therein, a plurality of column-stops adjustably supported upon said carriage, a dog mechanism mounted upon the frame and provided with a plurality of 5 dogs in different planes to coöperate with said stops, a rock-lever mounted upon the frame to oscillate said dog mechanism, a pivotally-mounted bar carried by a fixed member, a pawl carried by the lower end of said 10 lever to engage said bar, a slotted plate carried by said lever, and a headed stop-pin extended through said plate to limit the travel thereof.
22. In a device of the class described, a carriage-frame, a carriage mounted to travel therein, a plurality of column-stops carried by said carriage, a casing pivotally mounted upon the frame, a dog pivoted within said casing and projected therefrom under spring 15 tension, a secondary dog disposed at one side of said casing and means for normally retaining said tension-dog in alinement with said stops.
23. In a device of the class described, a carriage-frame, a carriage mounted to travel therein, a plurality of column-stops carried by said carriage, a casing pivotally mounted upon the frame, a dog pivoted within said casing and projected therefrom under spring 20 tension, a secondary dog disposed at one side of said casing, a spring disposed between said casing and the frame, a reciprocatory rod upon which said casing is mounted, and a cushioning-spring for said rod.
24. In a device of the class described, a carriage provided with a column-stop, an oscillating dog mechanism to coöperate therewith, an actuating-lever for said mechanism provided with a bearing portion intermediate 25 of its ends, a casing provided at the lower end of said lever, a spring-pressed pawl pivotally mounted in said casing and provided with an inclined outer face, and means to engage said pawl to actuate said lever.
25. In a device of the class described, a carriage provided with a column-stop, an oscillating dog mechanism to coöperate therewith, an actuating-lever for said mechanism provided with a bearing portion intermediate 30 of its ends, a casing provided at the lower end of said lever, a spring-pressed pawl pivotally mounted in said casing and provided with an inclined outer face, a longitudinally-extending bar pivoted at one side, and an operating- 35 arm extending from said bar.
26. In a device of the class described, a carriage, a standard provided with a rack, a vertically-movable frame thereon, a pinion carried by said frame to engage said rack, a 40 gear carried by said frame to engage said pinion, an escapement-wheel mounted upon the shaft of said gear, and a dog mechanism to coöperate with said escapement.
27. In a device of the class described, a 45 carriage, a vertically-movable frame there-
- for, a standard provided with a rack, a pinion carried by the frame to engage said rack, a gear carried by said frame to engage said pinion, an escapement-wheel mounted upon the shaft of said gear, a dog mechanism to 50 coöperate with said escapement, a trip-lever disposed upon one end of the shaft of said dog mechanism, and a hand-lever carried by the opposite end thereof.
28. In a device of the class described, a carriage, a vertically-movable frame therefor, a standard provided with a rack, a pinion carried by the frame to engage said rack, a gear carried by said frame to engage said pinion, an escapement-wheel mounted upon 55 the shaft of said gear, a dog mechanism to coöperate with said escapement, a trip-lever disposed upon one end of the shaft of said dog mechanism, a hand-lever carried by the opposite end thereof, a lever carrying said pinion at its lower end, and a tension-spring engaging the upper end of said lever to retain said pinion in mesh with its rack.
29. In a device of the class described, a vertically-movable frame, a carriage supported thereby, means for controlling the movement of said frame, a trip-lever for operating said means, a pivotally-mounted stop upon the carriage to engage said lever, and a lug adapted to be thrown into or out of operative relation with the lower end of said stop.
30. In a device of the class described, a vertically-movable frame, a carriage supported thereby, means for controlling the movement of said frame, a trip-lever for operating said means, a pivotally-mounted stop upon the carriage to engage said lever, a lug adapted to be thrown into or out of operative relation with the lower end of said stop, and a pivoted arm mounted at one side of said lug and adapted to be interposed between the same and said stop to retain the latter in horizontal position out of the path of the trip-lever.
31. In a device of the class described, a carriage-frame, a vertically-disposed carriage traveling therein and provided with a pivoted removable book-holder, and supporting-brackets for the book-holder pivots carried at the lower portion of said carriage.
32. In a device of the class described, a vertically-disposed carriage, a book-holder frame pivotally mounted at the lower edge thereof to lie in a horizontal plane when opened, and independent platens pivotally mounted in said frame at the pivoted edge thereof so as to swing into a vertical plane when the holder is open.
33. In a device of the class described, a carriage, a book-holder mounted therein, platens pivoted upon said book-holder, back boards mounted on said holder for movement in parallelism thereto, and spring-arms carried by the holder and bearing against said boards.

34. In a device of the class described, a carriage, a book-holder pivotally mounted therein, a tension-arm pivoted below the pivot of the carriage, a rod carried by said holder, a sleeve slidably mounted on said rod and pivotally connected to said arm, a tension-spring disposed upon the rod to contact with said sleeve and means on said holder to engage said sleeve. 5
35. In a device of the class described, a carriage, a book-holder pivotally mounted therein, a tension-arm pivoted below the pivot of the carriage, a rod carried by said holder, a sleeve pivotally connected to said arm, a tension-spring disposed upon the rod to contact with said sleeve, a locking-latch pivoted upon the holder, a tooth upon said sleeve to engage the latch, and means for operating said latch. 15
36. In a device of the class described, a carriage, a book-holder pivotally mounted therein, a tension-arm pivoted below the pivot of the carriage, a rod carried by said holder, a sleeve pivotally connected to said arm, a tension-spring disposed upon the rod to contact with said sleeve, a locking-latch pivoted upon the holder, a tooth upon said sleeve to engage the latch, a pivoted operating-handle at the free edge of said holder, 25 and a rod from said handle to said latch. 30
37. In a device of the class described, a carriage, a book-holder pivotally mounted therein, a tension-arm pivoted below the pivot of the carriage, a rod carried by said holder, a sleeve pivotally connected to said arm, a tension-spring disposed upon the rod to contact with said sleeve, and a stop-face carried by said tension-arm and adapted to engage a fixed member of the machine when 35 the book-holder is in lowered position. 40
38. In a device of the class described, a carriage, a holder-frame pivotally mounted thereon, parallel platens pivotally mounted in said holder upon a rod extended parallel to the pivots of the holder, and a casing pivoted upon the holder-frame to embrace the same. 45
39. In a device of the class described, a vertically-disposed carriage, a book-holder frame pivotally mounted at the lower edge 50 thereof to lie in a horizontal plane when opened, a pivoting-rod carried by said frame at the pivoted edge thereof, and separated independent platens mounted upon said rod at opposite sides of the center of the frame. 55
40. In a device of the class described, a carriage, a frame pivotally mounted therein on a pivoting-rod at one side of said frame, and independent platens pivoted upon said frame at opposite sides of the center of said frame said platens tapering inward in their cross-section. 60
41. In a device of the class described, a carriage, a frame pivotally mounted therein at one side thereof, independent platens pivoted upon said frame at opposite sides of the 65
- center of the frame said platens tapering inward in their cross-section, and a casing mounted upon the pivots of the platens beyond said frame. 70
42. In a device of the class described, a book-holder comprising a frame, back boards disposed within said holder, crossed levers pivotally connected to said boards and holder at opposite ends thereof, means for permitting the travel of the pivot at one end 75 of said levers, oppositely-disposed spring-activated arms carried by the holder and adapted to engage said boards and means for adjusting the tension of said arms. 80
43. In a device of the class described, a book-holder comprising a frame, back boards disposed within said holder, an arm carried by the frame to engage said boards, a rod upon which said arm is pivoted, and a tension-spring surrounding said arm and engaging the frame and arm. 85
44. In a device of the class described, a vertically - disposed carriage - frame, a carriage mounted to travel horizontally therein, a book-holder pivoted within said carriage to 90 swing into a horizontal plane at the rear thereof, and means to control the travel of said carriage. 95
45. In a device of the class described, a vertically - disposed carriage - frame, a carriage mounted to travel horizontally therein, a book-holder pivoted to swing in said carriage toward the rear thereof, brackets for the book-holder pivots having elongated 100 open-ended slots therein, means for controlling the travel of said carriage horizontally, standards upon which said frame is adapted to travel vertically, and means for controlling the downward travel of the frame upon said standards. 105
46. In a device of the class described, a vertically - disposed carriage - frame, a carriage mounted to travel horizontally therein, a book-holder pivoted to swing in said carriage toward the rear thereof, means for controlling the travel of said carriage horizontally, standards upon which said frame is adapted to travel vertically, means for feeding said frame downward upon the standards, and means disposed upon the carriage 110 for engaging and automatically actuating said downward feed. 115
47. In a device of the class described, a vertically-disposed carriage, means for effecting a horizontal travel thereof, and a book-supporting device mounted upon said carriage comprising opposite boards having spring tension-arms normally bearing thereon to present the book in printing position. 120
- In testimony whereof I affix my signature 125 in presence of two witnesses.
